UNITED STATES PATENT OFFICE.

CHARLES GODSHAW, OF TRYON, NORTH CAROLINA.

DESIGN FOR A CLOCK-DIAL.

SPECIFICATION forming part of Design No. 28,932, dated June 28, 1898.

Application filed April 16, 1898. Serial No. 677,895. Term of patent 3½ years.

To all whom it may concern:

Be it known that I, CHARLES GODSHAW, a citizen of the United States, residing at Tryon, in the county of Polk and State of North Carolina, have invented a certain new and useful Design for Clock-Dials; and I do declare the following to be a full, clear, and exact description of the invention, such as will enable others skilled in the art to which it appertains to make and use the same, reference being had to the accompanying drawings, which form a part of this specification.

This invention relates to certain new and useful designs for clock-dials, and especially to a dial having for each hour-numeral thereon a representation of a distinct card of a suit of playing-cards, said representations of the cards appearing in a circular series on the dial.

My dial is clearly illustrated in the accompanying drawings, in which I have shown, in—

Figure 1, an elevation of the clock-dial embodying my design, and in Fig. 2 I have shown a cross-sectional view through the dial.

The design consists in a circular marginal line of the dial, within which appear, upon the surface of the dial, a series of representations of a suit of playing-cards arranged in a circular form, with the corners of their inner ends nearly in contact with one another, forming a space about the center of the dial,

which space has as its outline the twelve margins formed by the inner ends of the rectangular representations of the cards. In the center of the space having the outline described appears a picture of the king of the suit of cards, spots thereon indicating the suit. Beginning at the hour-numeral there appear in a rectangular outline space the one-spot or ace of the suit, for the second hour-numeral the two-spot, for the third hour, the three-spot, for the fourth hour, the four-spot, and so on in regular sequence until the eleventh hour is reached, when a representation of the bower of the suit appears, and for the twelfth hour a representation of the queen of the suit. Each numeral indicated by a representation of a playing-card is enclosed by a rectangular outline, and between each inclosure there appears a V-shaped space.

Having thus described my invention, what I claim as my design is—

The design for a dial for a clock, substantially as herein shown and described.

In testimony whereof I affix my signature in presence of two witnesses.

CHARLES GODSHAW.
